(57) **CLAIM**

We claim, the ornamental design for a detonator module with retention formations, as shown and described.

DESCRIPTION

FIG. 1 is a perspective view of a detonator module with retention formations according to the new design;

FIG. 2 is a plan view of the detonator module with retention formations of FIG. 1;

FIG. 3 is a view from a first side of the detonator module with retention formations of FIG. 1;

FIG. 4 is a view from an opposing second side of the detonator module with retention formations of FIG. 1;

FIG. 5 is an end view of the detonator module with retention formations of FIG. 1; and,

FIG. 6 is a view of a cross-section of the detonator module with retention formations taken along line 6-6 of FIG. 4. The broken-lines shown in the drawings represent portions of the article that form no part of the claimed design.
